No. 13998.

June 19- 1883.

UNITED STATES PATENT OFFICE.

JOHN NEIL, OF NEW YORK, N. Y., ASSIGNOR TO THE BIGELOW CARPET COMPANY, OF CLINTON, MASSACHUSETTS.

DESIGN FOR A CARPET.

SPECIFICATION forming part of Design No. 13,998, dated June 19, 1883.

Application filed November 28, 1882. Term of patent 3½ years.

To all whom it may concern:

Be it known that I, JOHN NEIL, of New York city, county and State of New York, have invented a new and original Design for Carpets, 5 of which the following is a specification.

The accompanying photograph illustrates a face view of my new design for carpets.

This invention relates to a new design for carpets and analogous fabrics; and it consists 10 of the new configuration of groups and figures that make up the groundwork of the carpet.

In the photograph it is shown that the carpet is ornamented with the principal figures marked A, B, D, E, and H. The figure A represents a fanciful leaf having nine points, 15 and containing in its body a series of decorated veins. Small rosettes are between the central upper series of three points and each of the lower series of three points. Below the stem of the leaf-like figure A is a square enlargement, 20 which connects with a figure, j, which is principally composed of leaves having serrated edges. The figure B is of irregular outline, with scalloped upper portion and saw-shaped lower wings, and has between these 25 wings a fanciful stem, a. From one side of the figure B extends the fanciful wing b, and above the figure B, and somewhat to the right of the same, is a fanciful figure, z, resembling a goblet in outline, and above this is the figure 30 D, which resembles a heraldic shield embraced by a scalloped border at the lower part. Between the figure D and the figure A is a figure, m, which also represents a fanciful leaf

laid in a horizontal position. Above the figure D is a figure, o, composed of three leaves that are joined to one stem. Below the figure D, and between it and the figure B, is a figure marked x, composed of serrated leaves, and above that is a figure, w, also composed, 35 principally, of serrated leaves. Above the figure o is a figure, e, composed of three serrated leaves that appear to project from the same stem, from which stem also extends the stem of the leaf-like figure o, and also the stem of 40 flower-like figure f. The geometrically-shaped field H is to the left of the figure e, and above a twig-shaped figure, d. The upper part of the field H is embraced by a border, h, which abuts against the field or figure B. Above the 45 figure A and to the right of the figure H is the ornamental figure E, which represents a fanciful vase standing in an inclined position upon an inclined base. Between the stem j of the figure A and the goblet-like figure z is a group 50 of serrated leaves, s. Another group of serrated leaves, n, is to the left of the figure H, and another group of serrated leaves, v, to the right of the figure E. From the upper part 55 of the figure E extends an ornamental spray, i. 60

I claim—

The design for carpet, consisting of the figures A B D E H a b z x s w o d e f m h j n i v, substantially as shown.

JOHN NEIL.
